(No Model.)

G. W. CRABB.
CHURN.

No. 520,561.

Patented May 29, 1894.

UNITED STATES PATENT OFFICE.

GEORGE W. CRABB, OF SAND LAKE, MICHIGAN, ASSIGNOR TO FRED S. CRABB
AND JACOB S. LOCKERBY, OF SAME PLACE.

CHURN.

SPECIFICATION forming part of Letters Patent No. 520,561, dated May 29, 1894.

Application filed September 25, 1893. Serial No. 486,363. (No model.)

To all whom it may concern:

Be it known that I, GEORGE W. CRABB, a citizen of the United States, residing at Sand Lake, in the county of Kent and State of Michigan, have invented certain new and useful Improvements in Churns; and I do hereby declare the following to be a full, clear, and exact description of the invention, such as will enable others skilled in the art to which it applies to make and use the same.

My invention relates to improvements in churns, and its object is to provide the same with certain new and useful features, herein-after more fully described, and particularly pointed out in the claims, reference being had to the accompanying drawings, in which—

Figure 1 is a vertical section of a device embodying my invention, on the line 1—1 of Fig. 2; Fig. 2 a plan view of the same with parts broken away to show the internal construction; Fig. 3 a detail of the pivot bearing of the yoke; and Fig. 4 a detail showing the construction of the yoke.

Like letters refer to like parts in all of the figures.

A represents the usual rectangular box, or vessel, having an upper removable portion A' secured by a bar B, which portion when removed permits access to the interior of the said vessel. Upon a suitable frame work L and at opposite sides of the same are knife edge supports M, upon which rests a yoke consisting of a transverse middle part H, which extends beneath the middle of the box A, and two vertical portions H' embracing the sides of said box and extending upward to about midway of said sides, from whence they extend outward at H'', having oppositely inclined under sides H''', to rest upon the knife edges M. An arm I depends from the middle of said yoke, to which is attached a vertically adjustable weight J, whereby the center of gravity of the device is adjusted to conform to different quantities of cream therein contained. Cleats N and N' are attached to the box A at each side of said yoke, which retain said box and yoke in proper relative position, and permit of freely lifting the box out of the yoke as occasion requires; a lever K is also attached to said yoke, whereby the device is operated.

C, C, are opposite vertical grooves in the vertical inner sides of the box, in which is a vertically movable and removable bar D, having rounded ends D' engaging and rotative in said grooves, which latter do not extend entirely to the bottom of the sides, and thus sustain the bar D above the bottom of the box A. To this bar is attached one side of a deflector plate E, the other side of which is vertically movable and normally rests on the side bars F, which together with the transverse bars F', form a rack, which is divided at the middle, and detachably secured in the bottom of the box A, by means of a button G and spurs G'. By disengaging said button the inner end of each portion of said rack may be raised and the sections removed from the box for cleaning.

As the box A oscillates in a vertical plane the cream flows alternately toward each end of the same, and is broken up and churned by flowing over the bars F', and also passes under and lifts the deflector E, as it flows in one direction and passes over and depresses said deflector as it passes in the opposite direction, this deflector further agitates the cream and exposes it to the air. Said deflector also imparts a rolling motion to the butter after separation takes place, whereby it is in a short time gathered into a single large roll.

It will be observed that the parts of this device are readily detachable and removable from each other for cleaning and also of simple and easy construction.

What I claim is—

1. In a churn, in combination with a box pivoted to vibrate on a horizontal axis, a deflector plate arranged in an inclined position within said box, and pivoted near its upper end to said box, and having its lower end detached and freely movable vertically, whereby the cream or products thereof pass alternately below and above said plate, substantially as described.

2. In a churn, in combination with a box, substantially as described, and having an opening at the top, and having vertical grooves in the sides of the same, a removable bar pivotally mounted in said grooves, and a deflector plate attached at the upper end to said bar,

and freely movable in a vertical plane at the lower end, substantially as described.

3. In a churn, in combination with a box substantially as described, to contain the cream and pivoted to vibrate on a horizontal axis, a rack divided near the middle, spurs in the ends of said rack engaging the ends of said box, and a button engaging the middle of said rack, whereby said rack is detachably

secured in the bottom of said box, substantially as described.

In testimony whereof I affix my signature in presence of two witnesses.

GEORGE W. CRABB.

Witnesses:

J. S. LOCKERBY,
LUTHER V. MOULTON.
